W. C. Greene,

UNITED STATES PATENT OFFICE.

WILLIAM R. MILLER, OF POLO, ILLINOIS.

CHECK-HOOK.

SPECIFICATION forming part of Letters Patent No. 364,276, dated June 7, 1887.

Application filed July 14, 1886. Serial No. 207,974. (No model.)

To all whom it may concern:

Be it known that I, WILLIAM R. MILLER, a resident of Polo, in the county of Ogle and State of Illinois, have invented certain new and useful Improvements in Check-Hooks and Terrets; and I do hereby declare the following to be a full, clear, and exact description of the invention, such as will enable others skilled in the art to which it pertains to make and use the same.

My invention relates to improvements in harness-terrets, and is fully described and explained in the following specification, and shown in the accompanying drawings, in which—

Figure 1 is a side elevation of the terret. Fig. 2 is a second elevation of the terret, looking in the direction indicated by the arrow in Fig. 1; Fig. 3, a section on the line *x y*, Fig. 2; Fig. 4, a view similar to that shown in Fig. 3, illustrating a slight modification in construction. Figs. 5 and 6 are enlarged views of the non-hinged end of the short segment or tongue and of the corresponding end of the longer segment, which forms the body of the ring.

The terret consists of a circular ring, 1, 2, and a standard, 11, by which it may be attached to the saddle in the usual manner. The ring is discontinuous, the short segment 2 being hinged or pivoted at 8 to the body 1 in such manner that the segment may be pushed inward, as indicated at 2', Fig. 3. The outward movement of the tongue is prevented by its engagement with the end of the ring. The manner in which such engagement prevents outward movement is evident from Figs. 5 and 6, in which 9 is a cone-like tenon attached to or formed integrally with the tongue 2, and adapted to fit into a corresponding mortise or depression, 14, in the end 40 of the ring 1. The neck 13 of this tenon is narrower than the body 9, as is also the corresponding portion of the depression 15 in the ring 1, and, consequently, when the segment is in position to engage the ring, the ends of the latter 45 are prevented from separating. The thickness of the tenon being less than that of the ring, the exterior face of the ring shows only a straight line of division or joint.

The interior face of the ring is provided with 50 a recess, 6, Fig. 3, in which lies a spring, 3, conforming approximately to the curve of the terret, and lies within its general surface. This

spring is attached to the ring at one end, 18, and its other end rests against the body of the tongue 2 in a groove, 17, which extends beyond the end of the spring. The groove is also throughout the greater part of its length of a depth exceeding the thickness of the spring, to allow the latter to move outward when flexed.

In operation, the rein to be introduced into the terret is placed against the tongue and pressed inward and upward, when, by the yielding of the spring 3, the tongue is permitted to rotate about its pivot 8 to the position indicated by dotted lines in Fig. 3, and the rein 65 passes within the terret. During this operation the radius of curvature of the spring is lessened and its middle portion is thrown outward in its groove, while its free end slides forward in the vacant portion 17 of the groove. 70 When the rein passes the end of the tongue, the reaction of the spring 3 instantly throws the tongue back to its normal position, and its entrance within the depression in the ring is facilitated and slight displacement corrected by 75 the cone-like form of the tenon. Lugs 16, placed, respectively, upon the end of the ring and upon the opposite end of the tongue, serve as guides in inserting the rein and prevent its slipping from its proper position. Like lugs 80 upon the opposite side of the ring preserve its symmetry, and are, with the former, the only variations from the usual outline of a terret.

Fig. 4 is a section similar to Fig. 3 of a terret having the spring normally farther below 85 the internal surface of the terret, to give space for bars 10 10, spanning the groove in which the spring lies. These bars are flush with the interior of the ring, and retain the spring within its groove.

The form of outline chosen for illustration—an apparently simple ring, with both segments arcs of the same circle—is preferred; but this form may be varied, while the construction remains substantially the same, and this may be 95 desirable, especially in the terret which serves as a check-hook.

What I claim is—

1. The combination, with the broken ring 1, provided with means for attaching it to harness, of the tongue 2, hinged to one of the terminals of the broken ring, and when in its normal position filling the gap in the ring, but free to swing inward about its hinge, the spring 100

3 tending to hold the tongue in its normal position, and the guiding-lugs 16 16 formed on the ring and tongue, respectively, near the ends of said gap, substantially as and for the 5 purpose set forth.

2. The combination, with the broken ring 1, of the tongue 2, pivoted to one of the terminals of the broken ring, the free end of the tongue being provided with the conical tenon 9, having the contracted neck 13, and the corresponding terminal of the ring being formed

with a conical seat, 14, and slot 15, to receive the tenon and neck, substantially as and for the purpose set forth.

In testimony whereof I have signed this specification in the presence of two subscribing witnesses.

WILLIAM R. MILLER.
